Inventor:
Herbert E. Keeler,
by W. W. Thomas Attorneys

UNITED STATES PATENT OFFICE.

HERBERT E. KEELER, OF NEW YORK, N. Y., ASSIGNOR TO THE ADAMS & WESTLAKE COMPANY, OF ILLINOIS.

CLOSET.

SPECIFICATION forming part of Letters Patent No. 538,168, dated April 23, 1895.

Application filed February 21, 1895. Serial No. 539,260. (No model.)

To all whom it may concern:

Be it known that I, HERBERT E. KEELER, of the city, county, and State of New York, have invented certain new and useful Im-
5 provements in Closets, of which the follow-
ing is a full, clear, and exact description.

This invention is intended, more particu-
larly, for use on railroad cars and upon steam-
ships and steamboats, but is applicable to
10 more general use; and may be employed with
dry closets or those flushed by water.

The invention is specially adapted for use
with that class of closets in which the seat is
constructed to be raised from the bowl or hop-
15 per in order to allow it to be conveniently
and neatly used as a urinal or slop recepta-
cle; and its object is to prevent urine when
voided or water thrown into the bowl or hop-
per from passing through the seat-opening
20 and finding its way to, and thus soiling or
wetting, the outer surface of the seat.

The invention is applicable to a closet having
a seat and lid capable of being raised to-
gether, as shown for example in the applica-
25 tion of P. G. Emery, filed of even date here-
with; or it may be used where the seat and
lid are independently raised, or even where
the seat is unaccompanied with a lid, pro-
vided its use is confined to that class of closets
30 in which the seat is susceptible of and adapted
for being raised for the purposes named.

In the accompanying drawings, Figure 1 is
a perspective view, partly in dotted lines, of
35 a closet embodying my invention, the seat
being down and the lid up. Fig. 2 is a simi-
lar view, the seat being raised. Fig. 3 is a
sectional view on enlarged scale, of a detail
of the invention.

Similar figures of reference indicate simi-
40 lar parts in the respective views.

1 represents the woodwork or casing forming
part of the closet fixture.

2 is the bowl or hopper, preferably con-
structed of porcelain. To the ledge or pro-
45 jection 3 forming a part of the casing 1 is
hinged the seat 4, while to the same ledge
may be hinged a lid 5.

To the under side of the seat 4 is hinged an
apron or shield 6 of substantially the shape
50 of the seat-opening, but somewhat larger so
as, when hanging in the operative position

indicated in Fig. 2, to overlap the edges of
said opening. The apron or shield is in-
tended to swing by gravity and is provided
with pins or pintles 6^a which rest and par-
55 tially turn in bearings 7^a of a hinging plate
7 secured to the under side of the seat 4 by
screws or otherwise. The plate 7 as shown
more particularly in Fig. 3, is furnished with
an edge or elongated shoulder 7^b of a length 60
equal to that of the part of the apron or shield
between the pins 6^a, the function or office of
which shoulder is to check the outward swing-
ing movement of the apron when the seat is
in the act of being lowered, and keep said 65
apron from striking against the front inner
surface of the bowl or hopper and damaging
the same. The normal position of the apron,
when the seat is down, is indicated in dotted
70 lines in Fig. 1, from which it will be seen
that it hangs free from contact with the bowl
or hopper, forming no obstruction to the use
of the seat for its accustomed purpose. The
outer surface of the apron is as shown in Fig.
75 3, slightly convex, and any water striking it
will the more readily be deflected from it and
enter the bowl or hopper; while any water
temporarily resting upon it will tend to drain
toward the flat flanged periphery of the apron
and thence to the bowl or hopper.

This invention entirely obviates the danger
of water reaching the outer surface of the seat.

With seats unprovided with this improve-
ment, water striking the under side of the
85 seat when the latter is raised is apt to run over
the edges of the opening and find its way to
the outer surface, with most objectionable re-
sults.

The apron or shield may be made of any
suitable material, but I prefer sheet metal 90
covered with enamel.

Having described my invention, I claim—

1. In a closet of the character described, a
hinged seat adapted to be raised, combined
with an apron or shield so hinged to the un-
95 der side thereof in relation to the seat open-
ing as to cover said opening when the seat is
raised, substantially as set forth.

2. In a closet of the character described, a
bowl or hopper and a hinged seat, the latter 100
adapted to be raised, combined with a gravity
apron or shield so hinged to the under side of

the seat in relation to the opening thereof as to cover the same when the seat is raised, and a stop for limiting the forward swinging movement of the apron or shield, substantially as set forth.

3. In a closet of the character described, a bowl or hopper and a hinged seat, the latter adapted to be raised, combined with an apron or shield having a concavo-convex surface, and so hinged to the under side of the seat in

relation to the opening thereof as to close the same when the seat is raised, substantially as set forth.

In testimony whereof I hereto set my hand and seal.

HERBERT E. KEELER, [L. S.]
